(57) **CLAIM**

The ornamental design for a baby play gym mat, as shown and described.

DESCRIPTION

FIG. 1 is a perspective view of a baby play gym mat, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top perspective view of the baby play gym mat, in another configuration of use.

The broken lines in the drawings depict portions of the baby play gym mat, that form no part of the claimed design.

1 Claim, 8 Drawing Sheets
